FOOTBALL PRACTICE APPARATUS

William F. Burke and Roger Connor, Athens, Ohio

Application June 19, 1950, Serial No. 163,954

3 Claims. (Cl. 273—55)

1

This invention relates to practice dummies and is particularly concerned with live football practice dummies which are articulated with respect to their support and which may move or be moved bodily in simulation of players in both offensive and defensive maneuvers.

An important feature of football training is the development of cooperative teamwork and timing so that the overall power of the team is far greater than the mere addition of the individual strength and skill of the separate players. In offensive plays such cooperation and timing is particularly important since the success of the ball carrier is frequently dependent upon the ability of the linesmen to open a path for him through the opposing team. In such a play not only must each linesman hurl his opponent in a given direction from the path selected, but such action must be in such timed relation with similar action by each of the other linesmen and in such timed relation with the movements of the ball carrier that a way is cleared for him in the exact manner ordered by the signals and at the precise moment when he has reached the line and is capable of profiting by it.

Practice dummies have heretofore been used in football training but for the most part such dummies have been individual and used primarily for tackling practice. Frequently such dummies are freely suspended by ropes to move without resistance, except in so far as their mass resists movement, in response to the player's attack. Block pieces have also been employed which are bodily movable in response to the concerted push by a group of players but in neither case do such devices simulate a group of separate opposing players and in neither case do they provide a means of practicing or demonstrating the role of each individual player with respect to his individual opponent either as to what he should do or the necessary relation of his timing with that of his fellow players.

In defensive practice it is also desirable to provide means by which the players may be trained to receive the shock of an opponent's attack and preferably to subject a line of individual trainees to the simultaneous shock of a charging line. None of the practice devices heretofore used is capable of simulating such experiences.

It is therefore among the objects of the present invention to provide an individual dummy which may be moved by the individual player in a manner such as to familiarize the player with his specific duties in relation to specific plays

2

which are to be carried out. In carrying out this object the dummy is both pivotally and bodily movable and arranged to resist such movement in the manner of resistance by an opposing player.

It is a further object of the invention to provide for a plurality of such dummies to simulate a line of defensive players so as to permit training of a group of players in cooperative and timed offensive play so that they may become skilled in opening a line for the back field.

Another object of the present invention is to provide a novel and improved dummy mounting whereby the practice dummy is supported for both pivotal and bodily movement so as to permit actuation by the player in simulation of deflection of an oncoming opponent.

Another important object of the present invention is to provide motivation for a dummy whereby the dummy may be propelled with respect to the player so as to give life-like simulation to the attack on the player by an opponent.

Another important object of the present invention is to provide a new and improved control mechanism whereby the coach or other supervisor may at his discretion and by remote control actuate the dummy in a simulation of attack.

Numerous other objects and features of the present invention will be apparent from a consideration of the following specification when taken in conjunction with the accompanying drawings, in which:

Figure 1 is a perspective view showing a fragmentary section of a plural arrangement of the dummies of the present invention, together with an illustration of the manner in which the players may attack the dummies in timed cooperative manner to open a path for the ball carrier.

Figure 2 is a view similar to Figure 1 showing the manner in which the device may be used in defensive training.

Figure 3 is a top plan fragmentary view partly in section showing the dummy mounting disclosed in Figure 2.

Figure 4 is a fragmentary sectional view taken on the lines 4—4 of Figure 3.

Figure 5 is a vertical transverse section taken on the lines 5—5 of Figure 4, and

Figure 6 is a detailed fragmentary section taken on the lines 6—6 of Figure 3.

In general terms the structure of the present invention may be defined as comprising a suitable dummy support by which a dummy or a

plurality thereof may be arranged in elevated position with respect to the playing ground, which support includes one or more track members within which a dummy supporting trolley is mounted from which the dummy is suspended by pivotal means so as to provide for pivotal motion of the dummy on a horizontal axis. The invention provides for a pivotal movement of the track on a vertical axis remote from the location of the dummy in such manner as to permit a deflection of the dummy by bodily side movement in addition to the horizontal pivotal movement of the dummy. Movement of the trolley supporting the dummy along the track is resisted by spring means so that in offensive play the action of the dummy is in simulation of the resistance of an opposing player. The spring resistance means further provides for propelling the dummy along the trolley so as to simulate the action of an attacking player and a remote control is provided so that a coach may simulate surprise attacks upon the players. By the use of a plurality of dummies an entire team may be simulated. The spring means is such that the dummies may resist movement by the players and the players may resist and halt, deflect and even reverse movement of the dummies. It will be understood that the dummies are not necessarily used in the manner here suggested during the practice and the invention provides all the desirable features of fixed or stationary dummies as well as dummies which are "alive" in the sense that they are suspended for free motion in response to attack by the player.

Referring more particularly to the drawings, it will be seen that the supporting structure of the present invention includes a horizontal main beam 10 preferably in the form of a channel beam maintained in any desired manner in elevated relation to the playing field as by the supporting posts 11 suitably mounted in securing anchors 12. It will of course be understood that the manner of supporting the beam 10 in elevated position is of no patentable significance and various supporting arrangements may be provided therefor.

Pivottally mounted between the upper and lower flanges 13 of the beam 10 by vertical pivot pins 14 there is one or more right angularly extending horizontal tracks 15 which are preferably of substantially angular inverted C-shape formation having a top cross web 16, side webs 17 and spaced lower flanges 18 (see Fig. 5). Mounted upon the flanges 18 of the track 15 are two pairs of rollers 19 of a trolley 20. The trolley 20 comprises a pair of spaced substantially triangular side pieces 21 arranged with an apex thereof extending downwardly between the space 22 formed between the flanges 18 of the track 16. The inner or forward end of the trolley 20, that is the end nearest the beam 10, is provided with a transversely extending axle 23 which passes through the side plates 21 and has mounted on either side one pair of the two pairs of rollers 19. At the outer or opposite end of the plates 21 a similar transversely extending axle 24 is provided on the external extensions of which the other pair of rollers 19 is mounted. The trolley also includes a transversely extending catch bar 25 which is located outwardly beyond the outer axle 24. At the downwardly extending apex of the triangular plates 21 there is also provided transverse pivot pin 30 upon which is suspended between the

plates 21 a dummy shaft 31 upon which is mounted the dummy proper 32 which may be of any desired shape, configuration or structure elected. The dummy shaft 31 is provided with a bearing portion 33 engaging the pivot pin 30 and extends upwardly therefrom to a point substantially in the plane of the axles 23 and 24 at which point the shaft terminates in a bifurcated portion 35 between the furcations of which there is mounted a pin 36 which is adapted to receive the inner end 37 of a dummy spring 38. The opposite end 39 of the spring 38 is engaged with the outer transverse axle 24. Between the plates 21 there is also provided a stop web 40 which is in vertical alignment with the rear face of the dummy shaft 31. This arrangement is such that the dummy shaft may be pivotally moved in clockwise direction about the pin 30 transverse of the track which movement is restrained by the spring 38. Opposite pivotal movement from the vertical is precluded by the upper portion of the dummy shaft abutting against the stop 40.

By this means of suspension of the dummy shaft on the trolley it will be noted that a certain amount of give is permitted when the dummy strikes or is struck by one of the players so that the dummy may yield under such force to move rearwardly with respect to the trolley which movement is restrained by the tension of the spring 38. However, it will be noted that by means of the web 40 the spring is restrained against movement of the dummy forwardly of the pin 30 and during playing action no such forward movement with respect to the pin or the trolley is permitted.

The inner or forward axle 23 of the trolley 20 is engaged by the outer end 43 of an elongated driving spring 41 which extends within the track 15 towards the beam 10, its opposite forward end 42 being secured to the vertical beam pivot pin 14. As will be hereinafter explained the spring 41 is normally under tension when the trolley is in its outer position and upon release of the trolley the spring 41 acts to propel the trolley with the dummy towards the direction of the beam 10. For retaining the trolley in its outer position with the spring 41 under tension, the catch bar 25 is engaged by a catch member 45 which is mounted at the outer end of the track for pivotal movement about a pivot pin 46. The free outer end of the catch 45 is engaged by the armature 47 of a solenoid 48 which upon energization draws the armature upwardly to rock the catch in clockwise direction, as shown in Figure 4, thus withdrawing the head 49 of the catch from engagement with the bar 25 and thus permitting the spring 41 to forcibly and rapidly draw the trolley inwardly towards the beam 10. While the solenoid 48 may be energized in any desired manner, or a mechanical equivalent for release of the trolley may be used, the solenoid is preferably controlled by means of a conductor 50 connected with a manual switch 52 which may be in the hands of the coach, indicated at 53. Thus by remote control the coach may release the trolley at any desired time with or without notice to the players (here indicated at 54) so as to simulate an attacking play by an opposing team.

Mounted adjacent the beam 10 on the under side of the track 15 and centrally located with respect thereto so as to be in direct alignment with the upper portion of the dummy shaft 31, there is provided a stop pin 60 which is mounted

within a stop casing 61 (see Figure 6) and which is urged in outward extension from the casing 61 by a spring 62. This arrangement is such that as the dummy is propelled inwardly toward the beam 10 by tension of the spring 41 it will strike the pin 60 which will yieldably stop the inward motion of the trolley toward the beam.

In order to provide for a side deflection of the dummy in simulation of a deflection of an on-coming player by the shoulder thrust or straight arm of the opposite player, the track 15 is pivotally mounted on the pin 14 as hereinbefore mentioned. In order to restrain the free lateral motion of the dummy there is provided a pair of oppositely disposed obliquely arranged struts, generally indicated by the numeral 70. The beam ends of struts 70 which are secured to the beam 10 by pins 71 while the opposite track ends of the struts 70 are secured between a pair of spaced ears 72 mounted on the sides of the track adjacent the outer ends of the track and are secured between such ears 72 by a pin 73. As best illustrated in Figure 3 the struts are composed of telescopic members including an outer piston element 74 and an inner cylinder element 75. Within the cylinder element 75 a spring 76 is mounted the outer end of which abuts the inner end of the piston element 74 and thus urges the piston element outwardly towards the track 15. It will of course be understood that a pair of oppositely disposed struts 70 are provided for each of the track members 15 and thus their opposite and equal thrust will normally retain the track in a position of normal angularity with respect to the beam 10. However, as the dummy is struck by a player or as a player strikes the dummy whether at its outer position as retained by the catch 45, or during its motion inwardly, a bodily deflection of the dummy sideways with respect to the player is permitted, which movement is restrained by the action of the spring 76 within the struts 70.

As briefly referred to hereinbefore, the present invention lends itself readily to the provision of a single supporting structure for a plurality of tackling dummies whereby the dummies may be arranged in formation so as to simulate an opposing team. As indicated in Figure 2, a second track 15a may be arranged for pivotal support on the beam 10 and be guided in such pivotal movement by the restraining influence of the struts 70a and a dummy 32a may be supported from a trolley 20a in the manner hereinbefore described with respect to the dummy 32.

As may be seen from Figure 1, in use as a charging line the team may move the dummies sideways or rearwardly against their motivating spring and thus "open holes" for the ball carrier. The essential training in timing for offensive plays is thus achieved, as well as coordination of line players with the back field. It will also be understood that the invention is in no way limited to football practice but may be used in various means and manner to simulate entirely different procedures as, for instance, in military training for bayonet practice and the like.

When used in defense training, as shown in Figure 2, the dummies are retracted against the tension of their springs and are latched in such retracted position. Upon release under the control of the coach the entire line of individual players is subjected to the shock of attack from the individual dummies.

Having thus set forth one preferred embodiment of our present invention it will be under-

stood that numerous changes, modifications, and the full use of equivalents may be resorted to in the practice of the invention without departing from the spirit or scope of the appended claims.

Having thus described our invention, what we claim and desire to secure by Letters Patent is:

1. In a practice device, a horizontal supporting beam, a track pivotally mounted at one end on the beam for movement about a vertical axis, means for yieldably restraining said track against pivotal movement including a pair of telescopic arms connected by one set of ends to the frame and by the other set of ends to the track at points spaced from the pivotal axis of the track, said arms having compression springs for yieldably resisting contraction thereof, a trolley mounted for movement on said track, means for pivotally supporting a dummy from said trolley for swinging movement about a horizontal axis, a stop on the trolley for disposing said dummy in a substantially vertical position when the dummy is against the stop, a tension spring connecting the dummy to the trolley for causing the dummy to rest against the stop, a tension spring connecting the trolley to the pivot for the track to urge the trolley towards said pivot, a latch for retaining said trolley in a position spaced from the pivot, a solenoid for tripping the latch, and a switch operable for energizing the solenoid.

2. In a practice device, a horizontal supporting beam, a track pivotally mounted at one end on the beam for movement about a vertical axis, means for yieldably restraining said track against pivotal movement including a pair of telescopic arms connected by one set of ends to the frame and by the other set of ends to the track at points spaced from the pivotal axis of the track, said arms having compression springs for yieldably resisting contraction thereof, a trolley having two spaced parallel wheeled shafts mounted thereon with the wheels thereof rollingly engaging the track, means for pivotally supporting a dummy from said trolley for swinging movement about a horizontal axis, a stop on the trolley for disposing said dummy in a substantially vertical position when the dummy is against the stop, a tension spring connecting the dummy to one shaft for causing the dummy to rest against the stop, a tension spring connecting the other shaft to the pivot for the track to urge the trolley toward said pivot, a latch for retaining said trolley in a position spaced from the pivot, and means for tripping the latch.

3. In a practice device, a horizontal supporting beam, a track pivotally mounted at one end on the beam for movement about a vertical axis, means for yieldably restraining said track against pivotal movement including a pair of telescopic arms connected by one set of ends to the frame and by the other set of ends to the track at points spaced from the pivotal axis of the track, said arms having compression springs for yieldably resisting contraction thereof, a trolley having two spaced parallel wheeled shafts mounted thereon with the wheels thereof rollingly engaging the track, means for pivotally supporting a dummy from said trolley for swinging movement about a horizontal axis, a stop on the trolley for disposing said dummy in a substantially vertical position when the dummy is against the stop, a tension spring connecting the dummy to one shaft for causing the dummy to rest against the stop, a tension spring connecting the other shaft to the pivot for the track to urge the trolley toward said pivot, a latch for retaining

ing said trolley in a position spaced from the pivot, a solenoid for tripping the latch, and a switch operable for energizing the solenoid.
